UNITED STATES PATENT OFFICE.

DAVID WILLIAMS OGILVIE, OF BALBOA, CANAL ZONE.

LIFE-SAVING GARMENT.

1,109,140.

Specification of Letters Patent.

Patented Sept. 1, 1914.

Application filed February 11, 1913. Serial No. 747,817.

To all whom it may concern:

Be it known that I, DAVID W. OGILVIE, a subject of the King of England, residing at Balboa, Canal Zone, have invented new and useful Improvements in Life-Saving Garments, of which the following is a specification.

This invention relates to certain improvements in life saving garments and has relation more particularly to a device of this general character especially designed and adapted for use by persons operating aerial crafts, and the object of the invention is to provide a device of this general character having means of a novel and improved character whereby the wearer of the garment is effectively protected against injury as the result of a fall or from the possibility of drowning should the drop be in water.

20 The invention consists in the details of construction and in the combination and arrangement of the several parts whereby certain important advantages are attained and the device is rendered simpler, less expensive and otherwise more convenient and advantageous for use, all as will be hereinafter more fully set forth.

The novel features of the invention will be carefully defined in the appended claims.

30 In order that my invention may be the better understood, I will now proceed to describe the same with reference to the accompanying drawings, wherein—

Figure 1 is a view in elevation of an applied garment constructed in accordance with an embodiment of my invention; Fig. 2 is a view similar to Fig. 1 with certain of the concurrent parts being omitted; Fig. 3 is a view in elevation of one of the sections of the garment included in the present embodiment of my invention, showing certain of the parts in detail; Fig. 4 is a view in top plan of the parachute herein disclosed in extended position, the helmet coacting therewith being indicated in dotted lines; Fig. 5 is a somewhat diagrammatic view in end elevation of the parts as illustrated in Fig. 4, the coacting helmet being shown in full lines; Fig. 6 is a view in front elevation of the helmet, as herein disclosed, forming a part of my improved garment; Fig. 7 is a longitudinal vertical sectional view taken through Fig. 6, with certain of the parts in elevation; Fig. 8 is a view in front elevation of the face

protector, as herein embodied; Fig. 9 is a vertical view taken substantially centrally through Fig. 8; Fig. 10 is a view in elevation detached of one of the parts, herein disclosed as coacting with the parachute proper; Fig. 11 is a compound view illustrating in top plan and in side elevation one of the collars, as herein contained; Fig. 12 is a view similar to Fig. 11 illustrating a form of a second collar herein embodied; Fig. 13 is a view in end elevation of a bushing employed in the present embodiment of my invention; and Fig. 14 is a view in side elevation of the bushing disclosed in Fig. 13.

As disclosed in the accompanying drawings, 70 1 denotes a garment preferably of a union type and formed of any preferred fabric adapted to be worn over the general or ordinary aviator's garment and being provided around its waist portion with a reinforce or thickened portion 2 to which are adapted to be permanently secured in any desired manner the lower extremities of the flexible members or cords 3, to be herein-after more particularly referred to. The 75 neck or collar portion of the garment 1 is provided with a suitable fold through which is inserted a metallic collar 4, as is particularly illustrated in Fig. 12, one extremity of such collar being formed into an eye 5, while 80 the opposite extremity is formed into a hook member 6 adapted to coact with such eye as and for the purposes which are believed self-evident. While the garment 1, which may be termed a foundation suit, may be of any 85 desired type I prefer that it be somewhat after the nature of one piece bathing suit.

Coacting with the neck portion or collar of the garment is an auxiliary collar member 7, as particularly illustrated in Fig. 11, 95 having its upper marginal portion provided with an outwardly directed flange 8, the inner surface of such collar being adapted to be lined with superimposed layers of rubber and wool. This collar is adapted to be worn 100 around the neck of the aviator. In order to maintain this auxiliary collar 7 against displacement a clasp 9 is employed coacting with the openings or eyes 10 suitably produced in the end portions of the collar 7, as 105 is thought to be particularly illustrated in Fig. 11. This auxiliary collar 7 is also adapted to telescopically engage the collar 4 positioned within the fold at the neck portion of the garment 1.

Over the foundation suit or garment 1 is adapted to be worn a second garment 11 preferably made from water-proof and airtight material which is adapted to completely inclose the trunk of the body from the neck and the nether limbs and the arms above the elbows. As herein disclosed, the garment 11 is double-walled and capable of being distended by confined air, such air being insertible between the walls thereof through the medium of the valve 12, as is particularly shown in Figs. 1 and 2, it being understood that such air should not be forced between the walls of such garment 11 until after the same has been properly applied upon the aviator.

Between the walls of the garment 11 are positioned a plurality of perforated flexible rubber tubes 14 preferably positioned one around the foot, one around the heel and instep, one above and below each of the knee joints, one around the hips, one around the back below the arms and one around each of the arms adjacent the shoulder, such tubes being suitably anchored or secured to the opposed faces of the walls of the garment 11.

By the provision of the separable walls maintained distended by confined air, in connection with the perforated tubular members 14, it will be observed that if the aviator should encounter a fall and the safety appliance to be hereinafter more particularly referred to fail to operate, the possibility of injury will be reduced to a minimum, and the distended walls will serve in the capacity of a cushion, in a manner which is believed to be self-evident, the compressed air serving to absorb the shock of contact. It will also be observed that the inflation of the garment 11 will afford requisite buoyancy to maintain the person afloat should he drop in water.

The flexible members 3, hereinbefore referred to, are preferably four in number and are directed through suitable openings or apertures 15 produced in the front and rear of the garment 11 at substantially the waist line thereof, such apertures being preferably afforded by the flanged bushings 16, particularly illustrated in Figs. 13 and 14, whereby leakage of the confined air between the walls of the garment 11 is effectually prevented.

The upper extremities of the flexible members 3 are secured to the eyelets 17 carried by the outer extremities of the rods 18 and serving to limit the upward movement of such rods, the inner end of each of which rods is provided with an engaging member 19 adapted to create a pivotal engagement with the collar 4, such collar having its upper marginal portion suitably recessed, as indicated at 20 in Figs. 1 and 3, whereby such engagement may be effected, it being readily perceived that the flange 8 of the collar

7 serves to prevent displacement of the rod.

The rods 18 are normally disposed, when the garment is being worn, in substantially a vertical position, such rods being of such a configuration as to permit the same to lie snugly in contact with the outer surface of the garment 11, the length of the flexible members 3 being such as to limit the upward movement of such rods when they have been caused to assume substantially the horizontal. In order to limit the movement of such rods 18 one relative to the other when adjusted into substantially the horizontal, the eyelets 21 and 22 are provided on each of the rods 18 and to which are connected the flexible members 23 and 24, respectively, such members, however, permitting a movement of the rods into the substantially vertical or normal position. The members 23 and 24 are also suitably secured to the flexible body 25 constituting the parachute, which, when the rods 18 have been adjusted into a substantially horizontal position, serves to retard the drop of the aviator, it being readily observed that such adjustment of the rods 18 can be assumed either automatically or by the aviator extending his arms outwardly in substantially a horizontal plane from the body, as is particularly shown in Fig. 1. The body 25 is of an area greatly in excess of the area within the imaginary circle connecting the ends of the rods 18 when adjusted into a horizontal plane, whereby it will be observed that when resistance is being offered to the atmosphere a plurality of pockets will be formed, as is clearly indicated in Fig. 1, whereby the efficiency of the improved safety garment is greatly increased.

Each of the rods 18 is also provided at a suitable point intermediate its length with an eyelet 26 to which is secured a flexible member 27, the opposite extremities of all of such members 27 being suitably united, as at 28, and having connected at such point the operating flexible member 29 which is directed from the rear through an eyelet 30 projected upwardly from the top of the helmet 31, and then directed thereover and through a suitable opening 32 produced in the vizor 33 and extended downwardly and adapted to engage a suitable catch or clasp 34 carried by the garment 11 at the front thereof in close proximity to the waist line. The flexible member 29 is of such a length as to readily permit an engagement thereof with the catch 34 at the time the rods 18 are in their normal or substantially vertical position. By this arrangement, it will be observed that should the aviator fall head downward from his craft that he can grasp the flexible member 29 and thereby cause the rods 18 to assume a substantially horizontal po-

sition and thus bring the parachute 25 in a position to break the fall, as is believed to be clearly obvious.

The helmet 31 is formed preferably of an outer layer of thin cork covered by a light rubber cloth and of such configuration as to extend back on the head of the wearer in order to effectually protect the base of the skull. The interior of the helmet 31 is provided with a plurality of properly positioned tubes 35 preferably of rubber charged with compressed air and hermetically sealed together with a similar tube 36 inserted in the rim of the hat and over which the usual sweat-band is adapted to project, and such helmet is adapted to be maintained in proper position upon the head through the medium of the chain strap 37 and the additional straps 38 which are suitably secured to a collar 39 adapted to be worn about the neck of the wearer.

In order to protect the face against injury, I employ the face protector 40 of proper configuration provided with suitable visual openings 41 adapted to register with the eyes of the wearer. The face guard includes a suitable frame covered by a sheet 42 of mica provided throughout its area with minute perforations in order that no hindrance may be given to the breathing of the wearer. The guard is also provided with suitable air-charged tubes 43 to contact with certain portions of the face and preferably over the forehead and across the chin, such tubes being suitably covered with wool or the like in order to reduce to a minimum the possibility of irritation of the flesh. It might also be well to state that the sheet 42 of mica should be of such a color as to exclude the glare of the sun.

From the foregoing description, it is thought to be obvious that a life saving garment constructed in accordance with my invention is of an extremely simple and comparatively inexpensive nature and is particularly well adapted for use by reason of the effectiveness with which the wearer is protected against injury and it will also be obvious that my invention is susceptible of some change and modification without material departure from the principles and spirit thereof and for this reason I do not wish to be understood as

limiting myself to the precise arrangement 55 and formation of the several parts herein shown in carrying out my invention in practice.

I claim:

1. In combination with a garment and 60 head gear, of rods movably connected with the garment, means coacting with the garment and the rods for limiting the movement thereof in one direction, means connected to the rods and coacting with the head gear 65 for manually imparting movement to the rods in one direction, and a flexible body carried by the rods.

2. A device of the character described including a garment comprising separable 70 walls adapted to be distended by confined air and provided with means whereby such air may be inserted between the walls thereof, rods pivotally engaged with the inner wall of the garment, a flexible body carried 75 by such rods, and flexible means operatively connected with the rods and the inner wall of the garment for limiting the movement of the rods in one direction.

3. A device of the character described including a garment provided with a substantially rigid collar, rods pivotally engaged with such collar, a flexible body carried by such rods, and means operatively connected with the rods for limiting the movement 85 thereof in one direction.

4. A device of the character described comprising a garment provided with a substantially rigid collar, such collar being provided with recesses, rods detachably engaged within such recesses of the collar, a flexible body carried by such rods, and means for limiting the movement of the rods in one direction. 90

5. A device of the character described including a garment provided with a substantially rigid collar, such collar having recesses therein, rods detachably engaged within such recesses of the collar, an auxiliary collar telescopically engaged with the 100 first collar for maintaining such rods against displacement, a flexible body carried by the rods, and means for limiting the movement of the rods in one direction.

DAVID WILLIAMS OGILVIE.
